UNITED STATES PATENT OFFICE.

CHARLES R. SHORT, OF DAYTON, OHIO, ASSIGNOR TO GENERAL MOTORS RESEARCH CORPORATION, OF DAYTON, OHIO, A CORPORATION OF DELAWARE.

ENGINE-VALVE MECHANISM.

Application filed April 2, 1923. Serial No. 629,330.

The present invention relates to improvements in internal-combustion engines and more particularly to valve operating mechanism therefor.

5 Among the objects of the invention is to facilitate lubrication of certain parts of engine valve mechanism with which difficulties have heretofore been encountered.

10 Further objects and advantages of the present invention will be apparent from the following description, reference being had to the accompanying drawings, wherein a preferred form of embodiment of the present invention is clearly shown.

15 In the drawings:

Fig. 1 is a vertical section of a portion of an engine involving the structure of the present invention;

20 Fig. 2 is a vertical section of the sleeve fitting over the upper end of a push rod;

Fig. 3 is a detail of a part of the structure in Fig. 2;

Fig. 4 is a plan view of the detail shown in Fig. 3; and

25 Fig. 5 is a part vertical section of a modified form of the invention.

In the drawings a portion of one cylinder of an engine is shown which cylinder is provided with over-head valves of a common type. In Fig. 1 the cylinder 10 is provided with an integral head 11 in which is formed a valve seat 12 cooperating with valve 13. The valve 13 is of the usual form and operates in a guide 14 extending through the wall of pipe 15 which may be either an intake or exhaust pipe. The stem of valve 13 has the usual washer 16 at its upper end and secured from longitudinal movement thereon by a washer 17 and spring 18. The latter serves to retain the valve seated in the conventional manner.

40 Mounted upon the head of the cylinder is a suitable bracket 20 supporting a shaft 21 carrying rocker arm 22. The rocker arm 22 has one end resting upon the end of valve stem 13 and at its other end carrying means cooperating with push rod 30 by means of which the rocker arm is caused to actuate the valve.

45 50 Push rod 30 is provided in the usual man-

ner with a tappet 31 coating with cam 32 upon the cam shaft of the engine. The piston and piston rod are indicated at 35 and 36 respectively.

The push rod 30 is as shown in Fig. 1 55 provided at its upper end with a sleeve member 40 adapted to be securely fastened thereto. The upper end of sleeve member 40 is drilled to receive a plug 41 of oil absorbent metallic bearing material, which 60 plug is placed into the portion shown and is provided in its upper end with a hemispherical depression serving as a seat for a ball shaped piece 45 carried by the rocker arm 22. This ball shaped piece 45 is a 65 portion of pin 46 which extends through the end of the rocker arm and is threaded at the end opposite the ball and provided with a nut for the purpose of adjustment.

In a modified form of the invention the 70 sleeve 40' is attached to the push rod 30 and the pin 46' is provided at its lower end with ball 45' which is of a material such as is used for plug 41.

In producing the pin 46', the ball 45' is 75 first made and then brazed or otherwise secured to a tongue 48 on the lower end of pin 46'. Additional securing means may be had in a small flange 50 upon the lower end of pin 46', which flange may be turned over 80 the adjacent edge of the ball 45'.

The material of plug 41 and ball 45' preferably is of the material described and claimed in applications, Serial Nos. 582,550 dated August 17, 1922 and 613,780 dated 85 January 19, 1923, filed by Harry M. Williams and Alfred L. Boegehold. This material is preferably a porous bronze alloy containing a supporting filler material and is of such porosity that it will absorb several per cent of oil. By using such a material as this the rubbing surfaces may be kept well lubricated and a reserve supply of lubricant retained in one of the surfaces themselves so that infrequent attention on 95 the part of the operator is not apt to result in undue wear of the parts.

While the form of mechanism herein shown and described constitutes a preferred form of embodiment of the invention, it 100

is to be understood that other forms might be adopted, all coming within the scope of the claim which follows.

What I claim is as follows:

- 5 A push rod for internal-combustion engine valve operating mechanism having at its upper end a separate cup-shaped member open at its upper end and containing a plug

of porous metallic bearing material, said plug having its upper end concave in form ¹⁰ and shaped to form a seat for a downwardly extending coacting portion carried by a valve operating rocker lever.

In testimony whereof I hereto affix my signature.

CHARLES R. SHORT.
